UNITED STATES PATENT OFFICE.

ROBERT S. FOX, OF FORD CITY, PENNSYLVANIA.

VEHICLE JACK.

Application filed June 22, 1926. Serial No. 117,814.

My invention relates to improvements in vehicle jacks of the oscillatory lever type particularly to a novel and improved operating attachment therefor.

Now that low underslung automobile bodies have come into popularity the jacking up of a wheel to change a tire is a very disagreeable and difficult task. First—because it is necessary to lie prone on the ground and crawl under the car in order to properly locate the jack under the axle; and secondly—because of the lack of sufficient clearance between the car body for free manipulation of the operating handle. Only a very short handle can be used in the socket of the oscillatory lever owing to the lack of clearance and the operator has to manipulate the same from a very cramped prone or crouching position.

It is therefore the primary object of my invention to provide a novel and improved operating attachment which can be quickly attached to any type of oscillatory lever jack, and which will enable the operator to readily place the jack in position and manipulate it from a point well clear of the car.

Further, the invention comprehends a novel attachment of this class whereby the oscillatory operating lever of the jack is operated by a semi-rotary lever.

It is also an object of the invention to provide a device as set forth which will be very simple and durable in construction, highly efficient and convenient in operation and which will be relatively inexpensive of manufacture.

With the foregoing and other objects in view the invention comprises a novel combination and arrangement of parts to be hereinafter described and claimed, and in order that the same may be better understood, reference should be had to the accompanying drawings forming a part of this specification. It is understood, of course, that I do not propose to limit myself to the precise structural arrangement shown and described, but reserve the right to make such changes and modifications therein as fairly fall within the spirit and scope of the invention as claimed.

In the drawings,

Figure 1 is a side elevation of a jack of familiar form illustrating the application of my attachment thereto;

Figure 2 is a plan view of the attachment with the jack-lever connecting link removed

and showing the jack shank in section; and,

Figure 3 is a group perspective view showing certain of the elements of the attachment in disassembled relation. 60

Referring specifically to the drawing in which like parts are designated by similar reference characters throughout, numeral 4 denotes a jack having an oscillatory operating lever 5 of socketed form for the reception of a handle. Since the jack, as already stated, is of familiar type and, per se, forms no part of the present invention it need not be described.

My attachment comprises a pair of clamping plates 6 and 7 bolted together as indicated at 8 and 9 whereby to embrace the jack standard as clearly shown in Figs. 1 and 2. The plate 7 has an offset portion 7^a forming a space in which the jack standard 7^b may be inserted. By preference, I use spacer sleeves 9^a between the plate 6 and the offset 7^a of plate 7 through which the bolts 9 pass. These prevent the plates 6 and 7 from being buckled and also protect the bolts 9. 80

The outer side of the plate 6 is formed with a longitudinally disposed bearing 10 for the end of a short shaft 12 on which is keyed or otherwise rigidly fastened a socketed member 13 having a medial bifurcated crank arm 14. Of course the elements 12 and 13 may be integral if desired. The forward end of the socket member 13 defines a shoulder to bear against the proximate end of bearing 10, and end thrust of 90 the shaft 12 is prevented by a nut and washer 16, 17 upon the end thereof in contact with the other end of the bearing 10. 85

An operative connection between the bifurcated crank arm 14 and the socketed jack 95 lever 5 is established by means of a link 18, one end of which is pivotally connected in the bifurcation of the crank by pin 19, while the other end is engaged in an eye 20 of a wedge member 21 which latter is frictionally secured in the socket of the jack lever 5. 100

An elongated handle rod 22 has its forward end fixedly secured in the socketed member 13 by a pin 23 as shown in Fig. 2. The other end of the lever 22 is T-headed 105 at 24 and carries the laterally extending hand grip rod 25 as shown.

It is manifest that with this attachment the jack 4 can be readily inserted under an axle and from a point clear of the car body. 110 Oscillation of the socketed jack lever 5 to elevate the wheel will be conveniently accom-

plished in a self-evident manner through elements 13, 14, 18 and 21 upon short rotary oscillation of hand grips 25.

From the foregoing description read in connection with the accompanying drawing the advantages, conveniences and economies of my attachment, from both the manufacturers and users point of view, will be readily appreciated by those skilled in the art.

Having thus described my invention, what I claim as new and desire to secure by Letters Patent of the United States is:—

1. The combination with a jack having an oscillatory actuating lever; of a bearing member, means for clamping the bearing member to the jack, a shaft rotatably carried in said bearing, a crank fixedly carried by said shaft and a link connection between said crank and said oscillatory jack operating lever whereby said actuating lever will be oscillated upon partial rotations of said shaft.

2. The combination with a jack having an oscillatory operating handle; of a pair of clamping plates defining an intermediate recess for the jack standard, means for clamping said plates upon said standard, a bearing formed upon one of said plates, a shaft rotatably carried in said bearing, a crank fixedly carried by said shaft, and a connection between said crank and said oscillatory actuating lever whereby said actuating lever will be oscillated upon partial rotations of said shaft.

3. The combination with a jack having an oscillatory actuating lever; of a bearing member, means for clamping the bearing member to the jack, a crank member swingingly carried by said bearing member and movable in a plane substantially transverse with respect to the plane of movement of said actuating member, and a connection between said crank and said oscillatory actuating lever.

4. The combination with a jack having an oscillatory actuating lever; of a bearing member, means for clamping the bearing member to the jack, a crank member swingingly carried by said bearing member and movable in a plane substantially transverse with respect to the plane of movement of

said actuating member, and a pivotal link connection between said crank and said oscillatory actuating lever.

5. The combination with a jack having an oscillatory actuating lever; of an operating lever therefor, means for mounting said second lever for oscillatory movement in a plane substantially at right angles to the plane of said actuating lever, and an operative connection between the two levers.

6. An operating attachment for oscillatory lever jacks comprising a clamp including a pair of clamping plates having means for attachment to the standard of the jack, the major portions of said plates flatly engaging each other and projecting from said standard to a point approximately beneath the operating lever of the jack, a bearing carried by one of said plates and lying in a plane approximately at right angles to the pivot point of said oscillatory jack lever, a shaft in said bearing, a lateral crank carried by said shaft and movable in a plane substantially at right angles to the plane of movement of said jack lever, a connection between said crank and said jack lever, and means for oscillating said crank.

7. An operating attachment for oscillatory lever jacks comprising a clamp including a pair of clamping plates having means for attachment to the standard of the jack, the major portions of said plates flatly engaging each other and projecting from said standard to a point approximately beneath the operating lever of the jack, a bearing carried by one of said plates and lying in a plane approximately at right angles to the pivot point of said oscillatory jack lever, a shaft in said bearing, a socketed enlargement formed at one end of said shaft and forming a shoulder for engagement with one end of said bearing, a lateral crank carried by said shaft and movable in a plane substantially at right angles to the plane of movement of said jack lever, a connection between said crank and said jack lever, and an operating rod engageable in the socketed member for oscillating said shaft and crank member for actuating said oscillatory jack lever.

In testimony whereof I affix my signature.
ROBERT S. FOX.
